US0D1025492S

(12) United States Design Patent (10) Patent No.: US D1,025,492 S
(45) Date of Patent: * Apr. 30, 2024

(54) COSMETIC CASE

(71) Applicant: Canhao Chen, Shantou (CN)

(72) Inventor: Canhao Chen, Shantou (CN)

() Term: 15 Years

(21) Appl. No.: 29/919,948

(22) Filed: Dec. 7, 2023

(30) Foreign Application Priority Data

Jun. 14, 2023 (CN) 202330365703.4

(51) LOC (14) Cl. 28-03

(52) U.S. Cl.

USPC D3/205
